(57) **CLAIM**

The ornamental design for a barbell pad, as shown and described.

DESCRIPTION

FIG. 1 is a front perspective view of a barbell pad, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view showing the barbell pad in an alternate configuration.

The broken lines in the drawings illustrate the portions of the barbell pad, which form no part of the claimed design.

1 Claim, 9 Drawing Sheets
